UNITED STATES PATENT OFFICE.

EDOUARD P. BENOIS, OF PARIS, FRANCE, ASSIGNOR TO COTY, INC., OF NEW YORK, N. Y., A CORPORATION OF DELAWARE.

DESIGN FOR A LIP-STICK HOLDER.

Application filed March 14, 1924. Serial No. 8,928. Term of patent 14 years.

To all whom it may concern:

Be it known that I, EDOUARD P. BENOIS, holder, and a citizen of France, residing at Paris, France, have invented a new, original, and ornamental Design for Lip-Stick Holder, of which the following is a specification, drawing, forming a part thereof.

In the drawing,

thereof.

I claim:

The ornamental design for a lip stick holder substantially as shown.
